DESIGN FOR A BILLFOLD

Robert N. Lupfer and Louis A. Mueller, Springfield, Ohio, assignors to The Springfield Leather Products Company, Springfield, Ohio, a corporation of Ohio

Application February 18, 1935, Serial No. 55,489

Term of patent 7 years

To all whom it may concern:

Be it known that we, Robert N. Lupfer and Louis A. Mueller, citizens of the United States, residing at Springfield, in the county of Clark and State of Ohio, have invented a new, original, and ornamental Design for Billfold, of which the following is a specification, reference being had to the accompanying drawing, forming part thereof.

The figure is a front elevational view of a billfold, showing our new design.

The view shown is of that side of the billfold exposing the pockets which is generally referred to as the front side. The opposite or rear side of the billfold is plain and the billfold has no appreciable thickness.

We claim:

The ornamental design for a billfold, as shown and described.

ROBERT N. LUPFER.
LOUIS A. MUELLER.
